W. H. Tracy, Attorney

UNITED STATES PATENT OFFICE.

ROBERT CLARK McNEILL, OF JERSEY CITY, NEW JERSEY.

TRICK DEVICE.

1,207,960.

Specification of Letters Patent. Patented Dec. 12, 1916.

Application filed August 2, 1915. Serial No. 43,208.

To all whom it may concern:

Be it known that I, ROBERT C. McNEILL, a citizen of the United States, residing at Jersey City, in the county of Hudson and State 5 of New Jersey, have invented certain new and useful Improvements in Trick Devices, of which the following is a specification.

This invention relates to a trick device which may be employed as a means of diversion and to present the appearance of a relative heavy nail or the like, and utilized for attaching an object to a wall or floor so that it presents the appearance of being nailed or otherwise fastened to a wall or a floor and 15 without injury to the object thus fastened.

With these and other objects in view, the invention consists in certain novel features of construction as hereinafter shown and described and then specifically pointed out in 20 the claim; and in the drawings illustrative of the preferred embodiment of the invention, Figure 1 represents a coat suspended from a hook upon a wall with the improved device applied to one of the sleeves. Fig. 2 25 represents a hat resting upon the floor with one of the improved devices attached to the rim. Fig. 3 is an enlarged side elevation of the improved device in which the representation of the head and the adjacent portion 30 of the stock of an ordinary wire nail is employed, this figure being partly in section. Fig. 4 is a similar view, in which the representation of a head and the adjacent portion 35 of the stock of an ordinary cut nail is employed.

Corresponding and like parts are referred to in the following description and indicated in all the views of the accompanying drawings by the same reference characters.

The improved device comprises a body 40 portion 10 having a head 11, the body and head being formed to represent the head and the adjacent portion of the stock of an ordinary nail, preferably of large size. The body 45 10 and head 11 may be constructed to represent an ordinary wire nail, as in Figs. 1 and 3, or the same parts of an ordinary cut nail,

as in Figs. 2 and 4. The sides of the stock or body 10 extend in parallel relation and the lower end 12 of the stock is flat and at right 50 angles to the sides of the stock, as shown in Fig. 3. A relatively small needle 13, preferably of tempered steel, is inserted in the body 10 at the lower end thereof and extends in advance of the flat lower end of the body 55 10, as illustrated in Figs. 3 and 4. The needle will preferably be as small or fine as possible and enables the body 10 to be supported from a wall or floor with the lower end in contact with the garment and thus 60 presenting the appearance of a nail driven therein. When the needle 13 is thrust into a yieldable body such as a garment, the flat lower terminal of the stock sinks for a slight 65 distance into the soft material of the garment and thus materially increases the illusion and without injury to the garment.

The implement may be employed for supporting a portion of a garment by forcing the relatively fine needle through the garment and into the wall, as illustrated in Fig. 2. When thus applied, the garment appears 70 as if nailed to the wall while at the same time the fine needle will not injure the fabric.

A hat may likewise be apparently nailed 75 to the floor, as illustrated in Fig. 2, but without injury to the hat and thus deceive the owner of the hat or other garment until the trick is discovered.

The device may be employed to amuse and 80 divert without injury to the garment to which it is applied.

Having thus described the invention, what is claimed as new is:

An article of the class described including 85 a stock having its sides extending in parallel relation and a flat lower end merging without projections into the sides and at right angles thereto, and a pin directed downwardly from the center of the flat bottom of 90 the stock and projecting beyond the flat bottom of the same.

In testimony whereof I affix my signature.

ROBERT CLARK McNEILL. [L. S.]
